UNITED STATES PATENT OFFICE

2,549,954

TRUCK FOR CANAL LINING EQUIPMENT

Leonard R. Zimmerman, San Joaquin, Calif., assignor to Guntert and Zimmerman, Stockton, Calif., a partnership

Application September 13, 1948, Serial No. 49,046

4 Claims. (Cl. 105—163)

1

This invention is directed to, and it is an object to provide, novel rail mounted, supporting, and steering bolsters for the main equipment carrying frame of canal lining equipment; the present invention comprising a modification of the bolsters shown in co-pending application Serial No. 722,571, filed January 17, 1947.

A further object of the invention is to provide bolsters wherein the wheel trucks of each are adjustable laterally of the longitudinal center line of the bolster whereby to compensate for differential spacing of the bolster supporting rails extending along opposite banks of the canal.

An additional object of the invention is to provide bolsters, for the purpose described, which permit of substantial relative vertical adjustment between the same and the equipment carrying main frame so that the proper elevation of the latter may be maintained readily and without any loss of strength of the assembly.

Another object of the invention is to provide bolsters which are simple in structure, but very rugged and sturdy, notwithstanding the aforementioned adjustable features thereof.

A further object of the invention is to produce practical and reliable bolsters and which will be exceedingly effective for the purpose for which they are designed.

These objects are accomplished by means of such structure and relative arrangement of parts as will fully appear by a perusal of the following specification and claims.

In the drawings:

Figure 1 is an elevation of an equipment carrying main frame, of canal lining equipment, in position in a canal, and supported at opposite ends by the modified type of bolsters which comprise the present invention.

Figure 2 is a side elevation of one of the bolsters.

Figure 3 is a top plan view of the same.

Figure 4 is an enlarged fragmentary elevation, mainly in section, showing the vertically adjustable swivel mounting as employed in connection with each of the wheel trucks.

Referring now more particularly to the characters of reference on the drawings, each bolster is indicated generally at 1, and the same are used in pairs wherein said bolsters are transversely spaced, riding rails 2 extending lengthwise along opposite banks 3 of a canal 4 which is to be lined.

The bolsters 1 are rigidly affixed at opposite ends to an equipment carrying main frame 5 which extends transversely of the canal 4 in spanning relation thereto, and includes a frame

structure depending in generally symmetrical relation into said canal. The main frame 5 carries the equipment (not shown) for either sub-grading, laying the cement lining, or finishing said lining of the canal; such equipment forming no part of the present invention.

Each of the bolsters 1 includes a rigid longitudinal bolster beam 6, and opposite ends of the main frame 5 are affixed to the adjacent bolster beam 6 by upstanding and cooperating attachment flanges 7. In this way the bolsters 1 are rigidly mounted on opposite ends of the main frame 5; the bolsters riding the rails 2 whereby to support and steer said main frame 5, together with the equipment thereon, for motion lengthwise of the canal 4.

The bolsters 1 are each of the same construction and operation, and, therefore, a description of one will suffice for both.

Each bolster 1 comprises in addition to the rigid longitudinal bolster beam 6, a pair of swing frames 8 which project longitudinally from opposite ends of said beam; the swing frames 8 being attached to the adjacent ends of the bolster beam 6 by vertical axis pivotal mounts 9, whereby said swing frames are shiftable or swingable laterally in either direction through the range indicated by broken and dotted lines, respectively, in Fig. 3.

Each swing frame 8 is supported adjacent its outer end by a swivelly mounted wheel truck 10, and each such truck includes an inverted U-shaped saddle frame 11 in which a pair of longitudinally spaced wheels 12 are journaled; said wheels being peripherally grooved, as shown, for retention on the rails 2.

The swivelly mounted wheel trucks 10 each include a vertical spindle 13 fixed centrally on and upstanding from the saddle frame 11; such spindle slidably engaging in a vertical sleeve 14 affixed to the corresponding swing frame 8.

The vertical spindle 13 is cut exteriorly with a heavy thread 15, and an adjustment nut 16 is threaded thereon below the swing frame 8; a thrust washer 17 engaging between the adjustment nut 16 and said swing frame, whereby in any vertical position of adjustment of the spindle 13, it is free to rotate so that the related truck 10 may swivel in a horizontal plane. The adjustment nut 16 includes bores 18 for the reception of an actuating bar (not shown).

The vertical spindles 13 are adjustable up or down by the following described power mechanism so that substantial, non-manual adjustment can be accomplished independently of the nut 16.

This power mechanism comprises a fluid pres-

sure actuated power cylinder 19 disposed in the sleeve 14 vertically between a cap 20 on the latter and the spindle 13. The power cylinder 19 is operated to extend, or permit contraction thereof, by means of a fluid pressure control system, shown in part at 21. By operation of the cylinders 19, at opposite ends of the bolsters, the relative elevation of the bolster beams 6, and consequently the adjacent ends of the main frame 5 can be readily accomplished; the adjustment nuts 16 serving to provide a fine adjustment, and a final lock which permits the load to then be removed from the said cylinders.

In any position of vertical adjustment of the spindles 13 the corresponding wheel trucks can nevertheless freely swivel in a horizontal plane as may be necessary as the rails 2 are slowly traversed.

Additionally, with the employment of the swing frame 8, the rails 2 can be laid on top of the canal banks 3 without great exactitude for the reason that the bolster wheel trucks 10 are laterally adjustable to compensate for differential of the spacing between the rails 2 from bank to bank, i. e. transversely of the canal 4.

It will be seen that regardless of the position of lateral adjustment of the swing frame 8, that the wheel trucks 10 swivel in a manner so as to properly follow the rails 2. The permissible latitude of differential spacing of the rails is reflected diagrammatically in Fig. 3.

Under working conditions it may be desirable to lock the swing frames 8 in given positions of adjustment and to this end there is provided on each swing frame 8, at the top thereof, a locking quadrant 22 having a locking arm 23 overhanging the same. Each locking arm is fixed to the bolster beam 6 by bolts 24, and the locking quadrant 22 is adjustably secured to said arm by a removable bolt 25.

With the bolster construction, as described, the main frame 5 is effectively supported from the rails 2 extending along the canal banks 3; the arrangement being such that the main frame 5 is vertically adjustable, at either end, as working conditions may require, and the bolster structure permits the wheel trucks 10 to freely track the rails 2 even though there be considerable differential spacing of the latter.

It should also be noted that the bolster beams 6 can be leveled lengthwise of the direction of travel by adjusting the spindle 13 at one end to a greater extent than the spindle at the opposite end; this for the purpose of assuring of accurate vertical disposition of the main frame 5 transversely of the canal 4.

While herein described as applicable to canal

lining equipment, the invention may be applied in connection with any rail mounted concrete laying equipment.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. In a canal lining machine which includes a transverse main frame adapted to span the canal, a rigid bolster beam fixed to each end of the main frame, a pair of longitudinally spaced wheel trucks for each bolster beam, a mount for each truck, each mount being a swing frame pivoted at one end on a vertical axis to one end of one of the bolster beams, and one of said wheel trucks being connected with the opposite end of each swing frame, and means mounting the ends of the swing frames to which the wheels are connected for vertical adjustment relative to said trucks.
2. A machine as in claim 1 in which each truck frame is mounted on the swinging frame for turning movement about a vertical axis.
3. A machine as in claim 2 in which locking means are provided between the bolster beam and each swing frame for fixing the swing frame rigid with the bolster beam in any selected position of the swing frame laterally out from the longitudinal vertical plane of the bolster beam.
4. A machine as in claim 3 in which said last named means comprises a quadrant on each swing frame, an overhanging arm on each end of each bolster beam, and means for securing the quadrant to the arm at different points along the length of the quadrant.

LEONARD R. ZIMMERMAN.
